UNITED STATES PATENT OFFICE.

FREDERICK J. KALDENBERG, OF TARRYTOWN, NEW YORK.

DESIGN FOR A TOBACCO-PIPE.

SPECIFICATION forming part of Design No. 16,570, dated March 16, 1886.

Application filed January 28, 1886. Serial No. 190,130. Term of patent 7 years.

To all whom it may concern:

Be it known that I, FREDERICK J. KALDENBERG, a citizen of the United States, residing at Tarrytown, in the county of Westchester and State of New York, have invented and produced a new and original Design for Tobacco-Pipes, of which the following is a specification, reference being had to the accompanying drawings, forming part thereof.

10 Figure 1 is a side view of my newly-designed tobacco-pipe. Fig. 2 is a view taken from the under side, and Fig. 3 is a cross-section on line $\alpha\alpha$ of Fig. 1.

My invention relates to the external configuration of a tobacco-pipe; and the leading feature of my design consists in a diamond-shaped stem having flat straight sides where it joins the mouth-piece, and a smooth flattened surface on the under side of the bowl.

20 In the drawings, let A represent the bowl of the pipe; B, the stem, and C the mouth-piece thereof. The main portion of the stem B is of a diamond shape when viewed in cross-section. (See Fig. 3.) The extremity of the 25 stem B, where it joins the mouth-piece C, and likewise the end of the mouth-piece, are formed

with four flat sides, giving the appearance of a square-shaped or nearly square-shaped outline, as at b. On the under side of the bowl A is formed the smooth flat figure c.

What I claim as new, and desire to secure by Letters Patent, is—

1. The design for a tobacco-pipe herein shown and described, consisting of a stem diamond shape in cross-section, extending 35 from the upright bowl to a portion of the stem adjacent to the mouth-piece, the said latter portion being of right-angular cross-sectional outline.

2. The design for a tobacco-pipe herein shown and described, consisting of a stem diamond shape in cross-section, extending 40 from the upright bowl to a portion of the stem adjacent to the mouth-piece, the said latter portion being of right-angular cross-sectional 45 outline, and a flat diamond-shaped figure on the under side of the bowl.

FREDERICK J. KALDENBERG.
